UNITED STATES PATENT OFFICE.

FREDERICK G. WIELAND, OF BROOKLYN, NEW YORK, ASSIGNOR TO ANCHOR CAP & CLOSURE CORPORATION, OF BROOKLYN, NEW YORK, A CORPORATION OF NEW YORK.

METAL-SPINNING MACHINE.

1,359,554.

Specification of Letters Patent. Patented Nov. 23, 1920.

Application filed July 15, 1919. Serial No. 310,927.

To all whom it may concern:

Be it known that I, FREDERICK G. WIELAND, a citizen of the United States, residing at Brooklyn, in the county of Kings, State 5 of New York, have invented certain new and useful Improvements in Metal-Spinning Machines, of which the following is a specification.

This invention relates to sheet metal 10 working, and specifically to improvements in machines for spinning sheet metal articles. In the form hereinafter described the machine is adapted for the spinning of closure caps suitable for use on vessels or containers used for the packing of food and 15 similar purposes, although it is obvious that by changes in design of the metal shaping parts the machine may be adapted to the manufacture of articles of different forms 20 and for other uses.

In the class of machines to which this invention pertains there are employed at present machines containing turrets, both intermittently and continuously operated, which 25 carry a plurality of mandrels upon which the sheet metal articles are carried and formed. In such machines it is customary to associate rotary forming devices with said mandrels so that the articles carried by the 30 latter are presented to the forming devices in the course of the rotation of the turret. It is customary in machines at present employed, also, to lock the turret during its pause periods, while mandrels are associated 35 with the forming devices, so as to insure the proper coöperation of said devices.

My present invention pertains to machines employing these several features, and my invention resides in novel arrangements 40 of parts whereby distinct advantages are secured in the direction of certainty and accuracy of operation and provision for effecting adjustment of coöperating metal forming parts. By virtue of the increased certainty and accuracy of operation resulting 45 from the novel construction embodied in my invention, the machine is capable of much faster operation than has been practical to employ in machines heretofore, and 50 a uniform and better product is secured. These considerations are of great importance, particularly in the manufacture of cap closures designed for use on packing vessels such as bottles and jars, and particularly 55 caps of the screw variety, which are

characterized by including portions adapted for making engagement and coöperating with screw-threads or other mechanical seating or retaining members on the vessels to which the caps are to be applied. Speed of 60 operation is important in securing increased output, whereby such articles may be manufactured and supplied to the packers at decreased cost, and certainty and accuracy of 65 operation are important in insuring the production of articles of uniform shape and structure which do not require inspection, and which are certain to make proper fit with the vessels upon which they are employed. 70

For the purpose of securing positive operation of the machine it is an object of my invention to provide a structure wherein the forming members are positively actuated in their coöperation with the mandrels, and 75 wherein there is positive interconnection between the turret operating mechanism and the mechanism which operates the forming members so that there is perfect articulation and timing of said portions of the machine. 80

For the purpose of securing uniformity in the product it is a purpose of my invention to provide a construction wherein suitable 85 adjustments may be effected in the metal forming members whereby to secure their accurate articulation and coöperation.

Other and further objects of my invention will be obvious upon a complete understanding of the embodiment thereof now about to be described, or will be pointed out 90 hereinafter or in the appended claims, reference being had to the accompanying drawings forming a part of this specification, and in which Figure 1 is a top view of a machine embodying my invention; Fig. 2 is a sectional elevation taken substantially on line 95 2-2 of Fig. 1, and illustrating the relationship of the forming mechanism; Fig. 3 is an end elevation of the left hand end of Fig. 1, showing the turret actuating and controlling mechanism; and Fig. 4 is a side sectional elevation taken substantially on line 100 4-4 of Fig. 2.

In the following description, which is made by reference to the said drawings, 105 similar reference characters are applied to similar parts throughout, duplicate reference characters indicating duplicate parts.

The frame 1 includes bearings 1^a in which is supported a turret shaft 3. On the 110

shaft is connected a turret 2 having four arms or wings forming bearings for mandrel shafts 4. The mandrel shafts have shoulders 4^a bearing against the end of the 5 turret portion on which said shafts are journaled and forming seats for the spinning heads 5 which have fluted forming faces 5^a. Turret shaft 3 also has pinned to it an actuating wheel 40 having the face 10 slots 40^a and marginal centering and locking notches 40^b. A bell crank locking and centering lever is pivoted at P and has an actuating arm 45 extending across the face of the wheel 40, and a locking arm 45' carrying a 15 tapering lug 46 associated with the rim of the wheel and adapted to fit in the tapering locking notches 40^b. The drive shaft 35 has bearings on the frame 1, and carries a spur pinion 51 which drives into a spur pinion 20 50 carried on a stub shaft 39 mounted in bearings 39^a. Stub shaft 39 carries an arm 41 equipped with a roller 42 at its outer extremity and adapted for coöperation with face slots 40^a of the actuating wheel 40. 25 On rotation of shaft 39 this roller is brought into contact with the arm 45 of the locking lever, and swings the same forwardly, thereby lifting the lug 46 out of a notch 40^b. The movement of shaft 39, through the instrumentalities of arm 41 and roller 42, also 30 actuates the wheel 40, after the fashion of a Geneva cam, thereby imparting intermittent rotary movement to shaft 3 and the parts fixed for rotation therewith. It will be observed that the arm 45 of the locking lever has a cam face 45^a arranged for association 35 with the roller 42 and lying on a radius concentric with the shaft 39, while at its lower extremity said actuating arm 45 has a sharp bevel at 45^b. It will also be observed from Fig. 3 that the roller 42 will ride off of the curved cam face 45^a just prior to the time that said roller disengages the active cam faces of the face slots 40^a. This disengagement of arm 45 will permit locking arm 45' 40 to drop until the lug 46 engages the margin of wheel 40, so that, said locking lever being free, the lug 46 will drop into engagement with a lock notch 40^b immediately one moves 45 to centering position. In this manner complete movement of the turret is insured, overthrow thereof is positively prevented, and the mandrels carried by the turret are accurately centered during the pause periods 50 of the turret's operation.

Each of the mandrel shafts 4 carries on the end opposite the spinning head a spur gear 36. All of the said spur gears 36 are driven by a spur gear 7 rotatably mounted 60 on the shaft 3, and pinned to a gear 8 which is in mesh with gear 9 carried on the drive shaft 35. By means of this train the mandrel shafts and spinning heads are continuously rotated during operation of the drive shaft 35.

During the course of the rotation of the turret 2, the spinning heads 5 are presented successively to the spinning anvils, one of which anvils, during the pauses in the movement of the turret, performs one operation 70 on the caps carried by the spinning heads, and the other of which anvils performs further operations upon such caps. These spinning anvils are carried on shafts 14 journaled in bearings provided at one extremity of each of rocking frames 12, which frames are pivoted on shafts 13 secured by set screws 13^a in bearings in the machine frame. Attached to the frames 12 concentric with shafts 13 are rocking arms 18 75 carrying at their extremities rollers 19. Said rocking arms 18 are adjustably clamped on the frames 12 by means of collars 18^a and bolts 18^b. One of said rollers 19 is arranged for coöperation with a cam 27 and 80 the other with a cam 28, which cams are rotatable on shaft 3, and are keyed to a pinion 29 which is actuated from the drive shaft by spur gear 23. The arrangement is such that upon the rotation of cams 27 and 28, 85 frames 12 are rocked toward and from the shaft 3 so as to be positively forced into coöperation with the spinning heads 5, and then released from coöperation therewith. The spinning anvils are carried at the left 90 hand extremities of shafts 14 and have forming portions arranged for coöperation with forming portions of the spinning heads 5. At their right hand extremities shafts 14 carry pinions 16 which mesh with pinions 30 95 rotatable on shafts 13. Pinions 30 are keyed to pinions 31, which latter are driven by spur gear 29. Through this train rotation 100 of the spinning anvils is accomplished.

It has been mentioned above that one of the spinning anvils 2 performs certain operations upon the articles carried by the spinning heads 5, and that the other spinning anvil 6 performs further operations on said articles. The nature of said operations, of course, will be dependent upon the contour of the spinning faces on the spinning anvils and the spinning heads which, of course, may be varied to produce the desired shaping of the product. In the forming 110 of screw caps for jars, and many other articles, it is desirable to provide the article with a fluting, for the purpose of stiffening the material, or for the purpose of providing a roughened surface to facilitate 115 its being grasped by the hand in application and removal. Such fluting may be formed on the skirts or annular portions of container caps or similar articles by providing the supporting faces of the spinning 120 heads 5 with suitable transverse grooves or ribs and providing the coöoperating forming face of one of the spinning anvils with mating ridges or grooves, as is well known in practice. Inasmuch as said irregularities in 125 130

the coöperating forming members must be meshed, adjustment is desirable to insure their proper coöperation. I have made provision for such adjustment in the arrangement of the driving pinions 36 and 16. As is best seen in Fig. 4, said pinions are provided with hub portions 36^a and 16^a bearing on the shafts on which they are carried, which hub portions may be split, and are encircled by clamping collars 11. These collars may be drawn in by means of the clamping bolts 11^a to securely bind the pinions upon the shafts. Loosening of the clamping bolts permits the rotational adjustment of the shafts and their carried forming members relative to the actuating pinions, so that the intermeshing portions of the spinning heads and spinning anvils may be arranged in proper coöperation.

Likewise it is desirable to provide for a longitudinal adjustment of the coöperating forming members. I accomplish this by the provision of the thrust collars 15 carried on the anvil shafts 14, with which they have screw-threaded engagement, and on which they are clamped by the clamping bolts 15^a. Said thrust collars have longitudinal bearing against the sections of frames 12 in which shafts 14 are journaled, as is plainly illustrated in Fig. 4. This arrangement permits the accurate longitudinal adjustment of shafts 14 relative to collars 15 so as to permit proper positioning of the spinning faces of the anvils relative to spinning faces of the spinning heads 5, and further insures the proper retention of the spinning anvils in proper longitudinal adjustment.

It is desirable, furthermore, to provide means whereby the extent of operation of the spinning anvils relative to the spinning mandrels may be varied and positively controlled for the accommodation of different weights of sheet metal, or for other purposes. I have made provision for such adjustment by means of the clamps 18^a and bolts 18^b. By this means rotational adjustment of rocking arms 18 relative to frames 12 may be effected, so that the closeness with which the anvils will approach the spinning heads may be varied.

Motion is imparted to the driving shaft 35 through pulley 37 or other suitable means, and from said driving shaft through differently timed transmission mechanisms to the three differently actuated portions of the machine. Through the arm 41 and Geneva activating wheel 42, intermittent rotational movement is imparted to the shaft 3 and the turret 2, locking of the turret in paused positions being accomplished by the locking arm 45^a and release of the turret being accomplished by the operation of arm 41 upon arm 45. Continuous rotation, at high speed, is imparted to mandrel shafts 4 through the train comprising pinions 9, 8, 7 and 36.

Continuous rotation is imparted to the anvil shafts 14 through the train comprising pinions 23, 29, 31, 30 and 16. Oscillatory movement is imparted to the rocking frames 12 through the action of cams 27 and 28 upon rocking arms 18. The articles partly formed by punching or other preliminary operations, are fed on to the spinning heads 5 in any suitable fashion and are carried by said heads upon the movement of the turret. Said articles are presented first to the operation of one of the spinning anvils, and upon the next advance of the turret, to the next spinning anvil. During the pauses in the movement of the turret, the anvils are moved positively to a predetermined operating position relative to the mandrels, so as to exert the necessary pressure upon the articles to effect their desired shaping. When completed, the articles are discharged from the spinning heads by push rods 48 suitably actuated.

By virtue of the construction and the several features above described, the machine may be built very compactly and very strong. By virtue of the direct connection between all operating parts, the machine may be operated at a great variety of speeds without requiring different adjustments and without loss of articulation.

Having thus described my invention, what I claim is:

1. In a metal spinning machine, the combination of a frame, a turret shaft rotatably mounted therein, a turret carried by the turret shaft, a rocking frame associated with the turret, said turret and rocking frame carrying coöperating spinning devices, means mounted on the turret shaft for actuating the turret, means mounted on the turret shaft for actuating the rocking frame to move the spinning devices into coöperation, a drive shaft, and transmission mechanism actuated through the drive shaft for operating both of said actuating means.

2. In a metal spinning machine, the combination of a machine frame, a turret shaft mounted therein, a drive shaft operable independently of the turret shaft, a turret carried by the turret shaft, turret operating means, a rocking frame supported in the machine frame in association with the turret, said turret and rocking frame carrying coöperating spinning members, rocking frame operating means mounted on the turret shaft, and transmission mechanism actuated from the drive shaft for actuating the turret operating means and rocking frame operating means to impart intermittent movement to the turret and the rocking frame.

3. In a machine of the class described, the combination of a machine frame, a turret shaft mounted therein, a drive shaft mounted in said frame and rotatable relative to the turret shaft, a turret carried by the

- turret shaft, a rocking frame mounted in the machine frame in association with the turret, an actuating wheel carried by the turret shaft and effective upon the turret, an actuating cam mounted on the turret shaft and effective upon the rocking frame, and means for operating said wheel and said cam from the drive shaft to impart intermittent movement to the turret and rocking frame.
4. In a machine of the class described, the combination of a machine frame, a spinning head operably mounted thereon, an anvil shaft operably supported on the machine frame, a spinning anvil carried by the anvil shaft, means for moving the anvil shaft to bring the anvil into operative association with the spinning head, and a thrust member rotatably engaging the anvil shaft for effecting graduated longitudinal adjustment of said anvil shaft relative to the spinning head.
5. In a machine of the class described, the combination of a machine frame, a spinning head mounted for orbital movement thereon, gearing for rotating the spinning head, an anvil shaft movably mounted on the frame, a spinning anvil carried by said shaft, means for operating the anvil shaft to place the anvil into and out of co-operation with the spinning head, gearing for rotating said shaft in synchronism with the spinning head, and a thrust member carried by the anvil shaft and operable for varying the adjustment of said shaft longitudinally to change the operative association of the spinning head and the anvil.
6. In a machine of the class described, the combination of a machine frame, a turret shaft operably mounted therein, a turret carried by the turret shaft, a rocking frame associated with the turret, an anvil shaft carried by the rocking frame, a drive shaft, and means on the turret shaft operated from the drive shaft and effective to operate the anvil shaft and rocking frame.
7. In a machine of the class described, the combination of a machine frame, a rocking frame operably mounted thereon, a spinning anvil carried by the rocking frame and movable into and out of operative position by movement thereof, a gear wheel, a cam conjoined thereto and operating on a common axis of rotation therewith, means driven by the gear wheel for operating the spinning anvil, means actuated from the cam for rocking the frame, and means for actuating the gear wheel.
8. In a metal spinning machine, the combination of a frame, a turret shaft rotatably mounted therein, a turret carried by the shaft, a rocking frame associated with the turret, mandrels carried by the turret, an anvil carried by the rocking frame, means mounted on the turret shaft for actuating the rocking frame, a drive shaft, and transmission mechanism driven thereby for operating both of said actuating means.

9. In a metal spinning machine, the combination of a frame, a turret shaft rotatably mounted therein, a turret fixed for rotation with the turret shaft, a rocking frame associated with the turret, mandrels carried by the turret, an anvil carried by the rocking frame, means mounted on the turret shaft for actuating the turret, means movable on the turret shaft for actuating the rocking frame, means movable on the turret shaft for actuating the mandrels, a drive shaft, and transmission mechanism associated therewith for operating all of said actuating means.

10. In a metal spinning machine, the combination of a machine frame, a turret shaft mounted therein, a drive shaft mounted therein, a turret carried by the turret shaft, turret operating means, mandrels carried by the turret, operating means therefor rotatable on the turret shaft, a rocking frame supported in the machine frame in association with the turret, rocking frame operating means rotatable on the turret shaft, and transmission mechanism actuating the turret operating means and rocking frame operating means and the mandrel operating means to impart intermittent movement to the turret and the rocking frame, and continuous movement to the mandrels.

11. In a machine of the class described, the combination of a machine frame, a turret shaft mounted therein, a drive shaft mounted in said frame, a turret carried by the turret shaft, mandrels carried by the turret, a rocking frame mounted in the machine frame in association with the turret, an actuating wheel carried by the turret shaft and effective upon the turret, an actuating cam mounted on the turret shaft and effective upon the rocking frame, a pinion on the turret shaft and effective upon the mandrels, and means for operating said wheel, said pinion, and said cam from the drive shaft to impart intermittent movement to the turret and rocking frame, and continuous rotation to the mandrels.

12. In a machine of the class described, the combination of a machine frame, a spinning head operably mounted thereon, a rocking frame, an anvil shaft operably supported on the rocking frame, a spinning anvil carried by the anvil shaft in operative association with the spinning head, and a thrust member screw-threaded on the anvil shaft and engaging the rocking frame and adjustable for selectively varying the position of said anvil shaft longitudinally to adjust the association of the spinning anvil and the spinning head.

13. In a machine of the class described,

- the combination of a machine frame, a spinning head mounted for orbital movement thereon, gearing for rotating the spinning head, an anvil shaft mounted for rocking movement on the frame relative to the spinning head, a spinning anvil carried by said shaft and movable into and out of coöperation with the spinning head by movement of the rocking frame, gearing for rotating said 5 shaft in synchronism with the spinning head, and means for varying the position of said shaft longitudinally relative to its gearing to adjust the operative association of the spinning head and the anvil.
14. In a machine of the class described, the combination of a rocking frame, an anvil shaft movably mounted on the rocking frame, a spinning anvil carried by said shaft and movable by movement of the rocking 10 frame, gearing for rotating said shaft on the rocking frame, and a thrust collar adjustably associated with the rocking frame and anvil shaft for varying the adjustment of said shaft longitudinally to adjust the op- erative association of the spinning head and 25 said gearing.
15. In a machine of the class described, the combination of a machine frame, a turret shaft operably mounted therein, a rocking frame associated with the turret shaft, 30 an anvil shaft carried by the rocking frame, a drive shaft, and means on the turret shaft and operated from the drive shaft and effective upon the anvil shaft and rocking frame to impart intermittent oscillatory movement 35 to the latter and continuous rotary movement to the former.
16. A metal spinning machine comprising in combination a turret carrying planetary mandrels, a rocking frame carrying a rotary 40 anvil; a turret shaft; actuating means disposed axially on the turret shaft for transmitting movement to the turret, the mandrels, the rocking frame, and the rotary anvil; a drive shaft; and means mounted there- 45 on for operating the actuating means in synchronism.

FREDERICK G. WIELAND.
